(57) **CLAIM**

The ornamental design for a head worn display wave-guide assembly, as shown and described.

DESCRIPTION

FIG. 1 is a perspective view of a head worn display wave-guide assembly showing our new design, the broken lines indicate environmental structure and form no part of the claimed design;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken-lines of the figures depict a head worn display as well as related elements and various portions environmentally thereof. These broken line features are depicted for illustrative purposes, and form no part of the claimed design.
